tion of Illinois

Original application March 10, 1947, Serial No.
733,582. Divided and this application Decem-
ber 4, 1950, Serial No. 199,019

2 Claims. (Cl. 308—2)

1

This application is a division of my copending application, Serial No. 733,582, filed March 10, 1947.

The invention relates to weighing scales, and is more particularly concerned with a bathroom scale of stamped sheet metal construction for lightness, durability, and economy.

The principal object of this invention is to provide punched sheet metal hangers or fulcrum bearings for support of the platform on the wishbone levers and for fulcrum support of the one wishbone lever on the other. Hangers of this general type are well known, as shown, for example, Sutton Patent 2,293,572, issued August 18, 1942, but they were heretofore of cast construction and required machining of the knife-edge portions, thus making these parts too expensive, not to mention the fact that it was very difficult to produce the knife-edges in coplanar relationship by that method. Furthermore, the knife-edges thus formed were not durable and could be easily dulled and could not be produced to the desired sharpness in the first place, due to the heavy cast construction. In accordance with my invention, the generally U-shaped hangers are in the form of sheet metal punchings having outwardly projecting fulcrum portions on the upper ends of the arms of the U, on the bottom of which knife-edge fulcrums are provided by bevelling the edges of these projecting portions both one way, another knife-edge fulcrum being provided between the arms of the U on top of the cross-portion by bevelling the edge of this portion the same way, thereby insuring knife edges which are not only of the desired sharpness but truly in coplanar relationship, inasmuch as they are all in the same plane face of the member. The punchings are subjected to heavy pressure along their edges between dies to provide the knife edges as distinguished from a machining operation, thus producing edges which are more accurate in quantity production as to alignment. The heavy die pressure also gives the edges work hardness by compaction of the metal which makes for longer wear and the punchings are finally suitably heat treated for further hardening to give still longer life.

The invention is illustrated in the accompanying drawings, in which—

Fig. 1 is a plan view of a bathroom scale made in accordance with my invention, with the platform removed, but indicating in dot and dash lines the location of the four legs of the platform for support of the platform by means of hangers on the wishbone levers;

Figs. 2 and 3 are enlarged sectional details on

2

the lines 2—2 and 3—3 at Fig. 1, looking in the direction of the arrows;

Fig. 4 is a sectional detail on line 4—4 of Fig. 1, and

Fig. 5 is a perspective view of one of the hangers shown in Figs. 2 and 3.

The same reference numerals are applied to corresponding parts throughout the views.

Referring to the drawings, the reference numeral 16 designates the generally rectangular sheet metal base of a bathroom scale on which a generally rectangular sheet metal platform 17 is supported on said base through the medium of the lever mechanism of my invention, indicated generally by the reference numeral 18. The latter, generally speaking, consists of a small U-shaped spider or wishbone lever 19, and a large generally triangular-shaped spider or wishbone lever 20, the two levers being interconnected by a hanger 21. It is common practice to fulcrum the large lever at one end on the base and to support the other end of the lever on a coiled tension spring, like that indicated at 22, which is suitably suspended in the dial supporting frame 23 that is mounted on the front end of the base, the spring being supported by means of a screw 24 and adjusting nut 25, so that the scale can be set back to zero if it gets out of adjustment. The small lever 19 is supported at one end on the base and at its other end on the large lever 20 so as to transfer its load to the large lever, the platform being supported at the front end on the small lever and at the rear end on the large lever. Two arms 26 project upwardly from the front corners of the base to support the lever 19, and two arms 27 project upwardly from the rear corners of the base for support of the lever 20. Two legs 28 project downwardly from the corners of the front end of the platform to rest on the lever 19, and two legs 29 project downwardly from the corners of the rear end of the platform to rest on the lever 20. The weight is indicated on a dial 30 rotatably mounted in the frame 23 and visible through a window 31 in the top of the dial housing 32 and operable by a pinion 33 meshing with a rack 34 that is suitably guided in the frame 23 for reciprocatory movement vertically and rests at its lower end on the front end of the lever 20, said rack being arranged to gravitate in proportion to the deflection of the levers 19 and 20 under load. Two coiled tension springs 35 are connected at their opposite ends to and stretched between the platform 17 and base 16 to hold the parts in assembled relation and permit picking up the scale by its platform.

In accordance with the disclosure in the parent application, the spiders or levers 19 and 20, instead of being of heavy cast iron construction, or of welded steel construction, have the bodies 36 and 37 thereof each made from a single piece of sheet metal formed between dies to the flanged and ribbed forms shown. Thus, the lever 19 has downwardly projecting marginal flanges 38 and 39 on the inner and outer peripheries for stiffness and strength, these flanges being integrally interconnected at the ends of the lever by flanges 40 for maximum strength and rigidity. The major portion of the web 41 of this lever is depressed to define channel shaped ribs 42 and 43 along the inner and outer peripheries for further reinforcement of the lever to reduce to a minimum distortion under load and avoid likelihood of the lever getting bent out of shape. In a similar manner, lever 20 has a continuous downwardly projecting marginal outer flange 44 and has a triangular shaped opening 45 in the center thereof defined by a downwardly projecting continuous flange 46 to lend stiffness and strength, and longitudinally extending ribs 47 are struck upwardly from the web 48 to reinforce the lever 20 in the region where heavy strains are concentrated by reason of the lever 19 transmitting its load to lever 20 at this point. It is clear in Fig. 1 that the close spacing of flanges 44 and 49 and ribs 47 in this region, plus the fact that the marginal flange 44 is rather abruptly widened on both sides of lever 20 at this region, as shown at 50, make for the necessary strength and rigidity so that lever 20 will not be flexed too much under load and ultimately get bent out of shape. The flange 49 is a continuous rectangular flange defining a rectangular opening 51 provided in the forwardly extending arm 52 on lever 20 through which the lower portion of the dial 39 projects. The flange 49 cooperates with marginal flange 44 to form a channel section on both sides of the arm 52 so that the arm has ample strength and rigidity even though so much of it is cut away to provide the dial opening 51. These two channels, incidentally, give enough strength to make it feasible to have the arm 52 of rather small width on both sides of the dial, as best appears in Fig. 1, so that the width of dial frame 23 can be reduced to a minimum, thus permitting use of a dial housing 32 of narrow width so that more foot room is left on the platform 17 on opposite sides of the dial housing. The flange 44 is notched at two points on the rear end of lever 20, as shown at 55 in Fig. 1, in register with the upwardly reaching arms 27 and has bevelled straight edges 56 filed or pressed on the upper ends of these notches to provide the equivalent of the knife edge fulcrums usually machined on the other types of levers, for fulcrum engagement in the bottoms of V-notches 57 provided in the upper ends of arms 27. In like manner bevelled straight edges 58 are provided on the end flanges 40 of lever 19 in notches 59 for fulcrum engagement in the bottoms of V-notches 60 provided in the upper ends of arms 26.

The web portion 41 of lever 19 has openings 61 and 62 punched therein near the front end of each arm of the lever, the metal from these openings being bent downwardly on one side of the openings to provide two spaced parallel vertical ears 63 on which the improved U-shaped hangers or fulcrum bearings 64, forming the subject matter of this application, for fulcrum support of the front end of the platform, are rockably mounted by their aligned outwardly

projecting end portions 65, the downwardly offset middle portions 66 being arranged to engage in the V-notches 66' provided in the lower ends of the legs 28 on the front end of the platform, as clearly shown in Fig. 3. The ears 63 have V-notches 67 provided therein to receive the bevelled edges 68 on the bottom of end portions 65 of hangers 64, and there is a bevelled edge 69 on top of the offset middle portion 66 to enter the V-notches 66' in the legs 28. The hangers 64 can thus rock about an axis established by the aligned outer knife edges 68 as the platform load is applied via legs 28 to the middle knife edge 69 which is parallel to but offset from the edges 68 in a downward direction. The hangers 64 are of stamped sheet metal construction and have the bevelled edges 68 and 69 formed thereon between dies under heavy pressure. This construction, compared with castings, is cheaper but better, because, when the three bevelled edges 68 and 69 are produced tapering to the same face of the piece, as shown in Fig. 5, there can be no room for doubt that these edges are all in accurate coplanar relationship, whereas it was a very difficult matter to obtain such coplanar relationship in cast hangers, like those shown in Sutton Patent 2,293,572, in quantity production. The compression of the metal at the edges 68 and 69 makes for hardness and longer wear without a hardening operation. The web 41 is cut away on diametrically opposite sides of openings 61, as indicated at 70, as continuations of the slots in the ears 63 terminating in the V-notches 67, to provide clearance for the arms 65 and permit the hangers 64 to be dropped into place in notches 67 from above the lever 19. In a similar way, ears 71 having V-notches 72 therein are bent downwardly from the web 48 of lever 20 on opposite sides of openings 73, the openings 73 in this case having diametrically opposed side extensions 74 to allow passage of arms 65 of hangers 64, the bevelled edges 68 of these hangers resting in notches 72 and the bevelled edges 69 being entered in V-notches 75 provided in legs 29 on the rear end of the platform.

The web portion of lever 19, as best shown in Fig. 4, has an ear 76 bent downwardly therefrom at the middle of the rear cross-portion to rest on the hanger 21 and thus transmit the load carried by the lever 19 to lever 20. The hanger 21 is bent from a short length of stiff wire of round section to provide coaxially aligned trunnion ends 77 and a straight middle crank pin portion 78 in offset parallel relation to the ends. The web portion 48 of lever 20 has an opening 79 punched therein for projection downwardly therein of the middle crank pin portion 78 of the hanger 21 and the ear 76, which has a V-notch 80 with a semi-circular crotch to fit on the crank pin portion. The trunnion ends 77 of hanger 21 are rotatably supported on top of the web portion 48 of lever 20 and are held against lateral displacement by spaced lugs 81 bent upwardly from the web 48 at opposite ends of the opening 79. A downwardly projecting lug 82 is also provided on the lever 19 at the middle of the back of the cross portion, as an integral extension from flange 39, which projects freely through a slot 83 provided in the web 48 behind and parallel to the opening 79, the lower end portion of the lug being bent rearwardly, as clearly appears in Fig. 4, to limit upward movement of the rear end of lever 19 and thereby prevent disassociation of the ear 76 and hanger

21 in event a person causes the levers 19 and 20 to oscillate more rapidly than usual in normal operation, as, for example, by resting only one foot on the platform and depressing the same and quickly releasing the pressure. The lever 19 is assembled in the scale by first entering lug 82 in slot 83 and then lowering the front ends of the arms to rest on arms 26. This portion of the scale obviously involves the same kind of inexpensive punching and forming operations as 10 in the provision of the ears 63 and 71 previously described.

It is believed the foregoing description conveys a good understanding of the objects and advantages of my invention. The appended 15 claims have been drawn to cover all legitimate modifications and adaptations.

I claim:

1. As an article of manufacture, a swingable fulcrum bearing for use in scales and the like, 20 said bearing being constituted by a piece of sheet metal having a generally U-shape with aligned outwardly reaching portions at the outer ends of the arm portions of the U, said outwardly reaching portions being provided with knife edges 25

in axial alignment on their lower faces and which are adapted to carry the bearing in a vertical plane upon a support for swinging movement about an axis coincident with said knife edges, and with the cross portion of the U having on its upper face a knife edge co-planar with and facing the other said knife edges, all of said knife edges being formed by cold working between dies under heavy pressure whereby the metal which constitutes such edges is compacted to enhance the work hardness of such edges.

2. A swingable fulcrum bearing as defined in claim 1 wherein all of said knife edges lie in the plane of one and the same face of the sheet metal.

MIKE A. PROVENZANO.
